UNITED STATES PATENT OFFICE.

WILLIAM S. HOUGHTON, OF BOSTON, MASSACHUSETTS.

PAVEMENT OR ROADWAY AND METHOD OF MAKING SAME.

No. 888,887.

Specification of Letters Patent.

Patented May 26, 1908.

Application filed September 23, 1907. Serial No. 394,093.

To all whom it may concern:

Be it known that I, WILLIAM S. HOUGHTON, a citizen of the United States, residing at Boston, in the county of Suffolk and 5 State of Massachusetts, have invented a certain new and useful Improvement in Pavements or Roadways and Methods of Making Same, of which the following is a full, clear, and exact specification, reference being had 10 therein to the accompanying drawings.

My invention relates to concrete pavements. Heretofore, pavements of this general type have been constructed in courses, comprising a foundation course of concrete 15 or broken stone, a binder and a wearing surface; the purpose of the binder course being to form a bond between the foundation and the wearing surface. As a rule, the wearing 20 surface contains a percentage of bituminous material and to a large extent this bituminous material is relied upon to secure a perfect adhesion between the wearing surface and the binding course, or, in cases where no binding course is employed, between the 25 wearing surface and the foundation. In such pavements, it is absolutely essential that the wearing course should adhere perfectly to the under course, otherwise, when the pavement is subjected to traffic, the 30 wearing course is very liable to slide, roll or buckle and finally break up. This tendency is exaggerated by the susceptibility of bituminous material to heat which softens it and thereby loosens the bond between the 35 wearing surface and the underneath course.

The object of my invention is to provide a pavement so constructed that any sliding, buckling or other disturbance of the wearing surface will be impossible.

Further objects are to provide a pavement of durable, efficient and economical 40 construction.

In the accompanying drawings, which illustrate my invention and in which similar 45 numbers refer to similar parts throughout the several views:—Figure 1 is a vertical cross-sectional view of a portion of my foundation or substructure, and Fig. 2 is a vertical cross-sectional view of a portion of a 50 completed pavement embodying my invention.

In the drawings, 1 designates a curb; 2, 2, broken or crushed stones; 3 a cement mixture and 4 a wearing surface.

My pavement is constructed in the following manner. After the ground or earth has

been made compact and smoothed, I then spread thereon a layer of crushed or broken stone, the stony elements preferably ranging in diameter from one to three inches, and 60 roll the same until it is compact. The depth of this layer of crushed stone may vary from four to eight inches. In parkways and similar roadways where the traffic is light, a foundation of four inches in depth 65 would probably suffice, but where the road is to be subjected to heavy traffic, the foundation should be from six to eight inches deep after being rolled. For reasons hereinafter explained, it is important that the stony 70 elements which make up this foundation layer should be of sufficient size to leave large voids throughout the foundation after it has been rolled.

I next prepare a mixture of sand or screenings and dry cement (preferably Portland cement), in the proportion of one part of cement to three or four parts of sand or screenings and spread this mixture over the surface of the foundation. The cement mixture is then washed, by water from a hose or other suitable appliance, into the voids in the foundation, where the cement sets and binds the stone foundation into a homogeneous mass. It is desirable and necessary 75 in this connection that the voids should be of a size sufficient to permit the cement mixture to percolate entirely through the foundation and fill completely the voids from the bottom up. This washing process is 80 repeated until the voids in the foundation have been filled up to a line ranging from one-quarter inch to an inch below the upper 85 surface or surface of the stone foundation, which at this stage presents a substantially smooth 90 surface of stone broken up by innumerable voids of varying depth and forms.

After the foundation has been thoroughly bound together in a monolithic mass by the setting of the cement mixture, it is then 100 ready to receive the wearing surface which may be composed or made up by any of the well known methods, or of any preferred composition.

The wearing surface when laid upon the 105 foundation, penetrates and fills up all the open voids in the upper portion of the foundation and is thereby, when hard, anchored to the foundation. It will be noticed that many of the voids are larger at their bottom 110 than at their top and in such cases, those portions of the wearing surface which fill

those particular voids act as anchors to hold the wearing surface in place. In a pavement so constructed, it is obvious that any sliding, shifting or buckling of the wearing surface is 5 absolutely impossible and the pavement is to all intents and purposes an integral body.

The principal advantages of my pavement constructed as above set forth are its economy of construction and wearing qualities. 10 The foundation layer of crushed or broken stone is rolled with the ordinary steam roller which enables the layer to be smoothed off rapidly and saves the expense of pounding or tamping the layer by hand. Furthermore, 15 more by rolling, a smoother and more even surface can be secured, and to this fact is largely due the wearing qualities of my pavement. Were the upper surface of the foundation layer rough and made up of alternate 20 stony projections and depressions, the wearing surface between the projections would in time wear away and the surface of the pavement would become uneven and thereby tend to break up. By having a comparatively smooth upper surface on the foundation layer, the erosive effect of traffic on the wearing surface does not result in roughening the surface of the pavement, and even when 25 the wearing surface has been worn away to 30 the foundation layer, the pavement is still smooth and even. In view of this feature, my pavement does not require a heavy wearing surface and it may be made compara-

tively thin if desired. This also conduces to economy of construction.

35

What I claim is:—

1. A pavement, consisting of a foundation layer of crushed or broken stone, the pieces of which lie closely together in a compact mass having a smooth upper surface, the voids in the lower portion of said layer being occupied by a cement mixture which binds all of the pieces of the layer into a monolithic mass, and a wearing layer anchored to the upper portion of the foundation layer by filling the upper voids thereof and being integral with the body of the wearing layer.

2. The process of making a pavement, consisting in laying a course of crushed or broken stone, rolling the same to compact the course and to smooth the upper surface, then filling the lower voids in said course with a liquid cement mixture, permitting said mixture to set and applying a suitable wearing surface to said structure in such a manner that the lower portion of said wearing surface fills in all the open voids in the upper surface of said course.

In witness whereof, I have hereunto set my hand, in the presence of two subscribing witnesses, this the fifth day of September, 1907.

WILLIAM S. HOUGHTON.
